UNITED STATES PATENT OFFICE.

HANS J. MÜLLER, OF NEW YORK, N. Y., ASSIGNOR TO HIMSELF AND
ALEXANDER LEVETT, OF SAME PLACE.

ELECTROPLATING-CIRCUIT.

SPECIFICATION forming part of Letters Patent No. 245,206, dated August 2, 1881.

Application filed May 21, 1881. (No model.)

To all whom it may concern:

Be it known that I, HANS J. MÜLLER, of the city, county, and State of New York, have invented an Improved Electroplating-Circuit, 5 of which the following is a specification.

The object of my invention is to provide certain new and useful improvements in electroplating-circuits for the purpose of preventing the secondary current of the plating-bath 10 from reversing the polarity of the machine.

The invention consists in a third or separate line which leads from a piece of carbon or other electric conducting material to the inner positive end of the magnet-wire or to a post connected with the said end of the magnet-wire. 15

In the accompanying drawings a diagram of my improved plating-circuit is shown.

A short description of this improved electroplating-circuit is given in my patent, No. 20 241,053, on dynamo-electric machines, dated May 3, 1881; but I did not claim the invention at the time, as it was to be the subject-matter of a separate application.

The magnets, the armature-coils, the binding-posts F' F², the binding-posts V and W, for the negative line X' and positive line X², respectively, leading to the bath, and the relay-magnet, resistance, and connections are all arranged as shown and described in the above-named patent. From the binding-post F', to which the inner positive end of the magnet-wire is attached, a wire, y, or separate line leads to a piece of carbon, z', or other electric conductor in the bath C. The piece of carbon z' is clamped by a piece of metal, a, to which the wire y is attached. This metal clamp a and the wire y, as far as it is immersed in the solution, is surrounded by a thick coating or layer, d, of gutta-percha, rubber, wax, &c., or other 30 material that is insulating, and at the same time liquid-proof. If desired, the wire y can be connected directly with the inner positive end of the magnet-wire; but I prefer the construction described above. Any kind of dynamo-electric plating-machine can be used; but preferably a machine with a protector to 40 guard against the secondary current is used. This separate line is indispensable, as the circuit could not otherwise be completed when

there is no work in the bath. As is well known, 50 a secondary current is produced in the cyanide solution or bath, and this secondary current discharges itself when but a small quantity of work is left in the bath and the polarity of the dynamo-electric machine is reversed. If all 55 the work is removed from the bath and the machine and the bath are not connected by the separate line y the secondary current will not be discharged, but remains in the bath until fresh work is placed therein, and the 60 moment the work is introduced the current is discharged and reverses the polarity of the machine, if the protecting-relay is not provided, or if it is inoperative; but if the machine and the bath are connected by a separate line, described above, the circuits will be changed considerably, for in this case the secondary current will be discharged as soon as all the work is removed, and the bath will be neutral when fresh work is placed into it. The circuit of 70 this secondary current will be changed accordingly if the machine is provided with a protecting-relay or not.

If the machine is not provided with a protecting-relay, or if this protecting-relay is inoperative, (which amounts to the same thing,) the circuit of the secondary current is as follows: From the anode m to the binding-post W, binding-post F², brusher O, commutator K, brusher N, post F', separate line y, to the bath— 75 that is, the secondary current will be discharged as soon as the work is removed from the bath and the bath is neutral. If the separate line had not been provided the secondary current would have been discharged through 80 the field-magnets, and the polarity of the machine would have been reversed, as described above; but if the machine is provided with an operative protecting-relay the secondary current will pass through the magnets, as described in Patent No. 241,053; for although the magnet-wires are much longer than those of the armature, they are also thicker, and thus present less resistance, and consequently the current passes through them and not through 85 the armature. A small part of the primary or working current passes from the anode directly to the carbon z', and for that reason 90 95

this piece of carbon must not be too large, for otherwise the quantity of work performed will be less and the field-magnets will be affected. If the circuits are followed on the diagram 5 it will be seen that the part of the primary or working current that passes from the anode to the carbon will encounter the primary current coming from the field-magnets between the post F' and the field-magnets. This small 10 part of the main current is carried along by the greater part of this current, (coming from the magnets,) and consequently this small part of the current is lost—that is, it cannot be used to excite the field-magnets. Therefore, 15 if the carbon z' is not very large, only a small quantity of the primary current will be lost; but such a small piece of carbon will always answer for the secondary current, the intensity

of which is much greater than that of the primary or main current. 20

Having thus fully described my invention, I claim as new and desire to secure by Letters Patent—

In an electro plating-circuit, the combination, with a dynamo-electric machine and with 25 a plating-bath, of the positive and negative wires connecting the machine and the bath, of a third or separate line connecting the machine and the bath, and of a piece of carbon or equivalent attached to the bath end of this separate 30 line, substantially as herein shown and described, and for the purpose set forth.

HANS J. MÜLLER.
